ILLUMINATED WHIRLING TOY

Arvin A. Gussa, San Diego, Calif.

Application August 13, 1948, Serial No. 43,990

4 Claims. (Cl. 46—47)

1

My invention relates to a toy, more particularly to an illuminated blimp toy rotating stand in which operation of the illuminated blimps causes light to automatically be ignited therein, and the objects of my invention are:

First, to provide a toy of this class having a rotating top on which illuminated blimps are mounted, which centrifugally actuates switch means causing electric lamps to be energized therein, which is very entertaining to children at night;

Second, to provide a toy of this class having novel winding means for the motor thereof;

Third, to provide a toy of this class having a very simple and economical motor which is very easy to operate and very reliable;

Fourth, to provide a toy of this class having novel over-running clutch means;

Fifth, to provide a toy of this class employing very simple switch means, in connection with the blimp-supporting arm, which is actuated by centrifugal force acting on the suspended pivotally mounted blimps at the end of said arm;

Sixth, to provide a toy of this class which may be continually wound while in operation; and

Seventh, to provide a toy of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings, and to the characters of reference thereon, forming a part of this application, in which:

Fig. 1 is a top or plan view of my toy; Fig. 2 is a side elevational view thereof; Fig. 3 is a sectional view taken from the line 3—3 of Fig. 2; Fig. 4 is an enlarged fragmentary bottom plan view taken from the line 4—4 of Fig. 3; Fig. 5 is an enlarged fragmentary sectional view of the pawl base and pawl of my toy; and Fig. 6 is an enlarged fragmentary sectional view taken from the line 6—6 of Fig. 2, showing parts and portions in elevation to facilitate the illustration.

Similar characters of reference refer to similar parts and portions throughout the several views of the drawings.

The base 1, winding handle 2, roller 3, strap 4, drum 5, gears 6 and 7, spring 8, shaft 9, pawl base 10, pawl 11, blimp supporting arm 12, blimps 13 and 14, switch contacts 15 and 16, bat-

2

teries 17, conductors 18 and 19, and the lamps 20, constitute the principal parts and portions of my toy.

The base 1 is a box-like or round structure having resilient feet 1a supporting the same, and rotatably mounted in this box-like or round base 1 is the roller 3, supported on the bracket 3a, all as shown best in Fig. 4 of the drawings. The winding handle 2 is preferably a rigid rod having a T-head 2a thereon, projecting outwardly of the base 1, all as shown best in Figs. 2 and 3 of the drawings. Connected to the inner end of this winding handle 2 is the flexible strap 4, which passes over the roller 3 and is wound around the drum 5, and connected thereto at its opposite end by the pin 5b, shown best in Fig. 4 of the drawings. This drum 5 is rotatably mounted on the bracket 5c and is provided with an annular groove 5a at its peripheral surface, in which the spring 8 is engaged. This spring 8 is fixed to the drum 5 by means of the pin 5e at its one end, and is secured to the inner side of the base by the hook 5d at its opposite end. Fixed to the normally upper end of the drum 5 is the spur-gear 6, meshing with the pinion 7, fixed to the shaft 9, on which the pawl base 10 is secured. This pawl base 10 is provided with a downwardly extending shank 10a, positioned internally of the hollow shaft 9, as shown best in Fig. 3 of the drawings. Pivoted on the upper side of the pawl base 10 by means of the pin 10c is the pawl 11, which is a solid-rod-like member, engaged by the spring 11a tending to force the same against the stop 10b of the pawl base 10, which forms a solid abutment for the pawl 11 when pivoted in one direction. The blimp-supporting arm 12 is provided with a downwardly extending shank 12c at its middle portion, which is rotatably mounted within the hollow tubular shank 10a of the pawl base 10, all as shown best in Fig. 3 of the drawings. Pivoted on the outer ends of the pins 13a and 14a are the illuminated blimps 13 and 14. These blimps 13 and 14 are provided with U-shaped brackets 13c and 14c through which the pins 13a and 14a extend. The blimps 13 and 14 are provided with contacts 13b and 14b, respectively, which are arranged to engage the contacts 15 and 16 on the extended arm portions 12a and 12b, respectively, of the supporting arm 12. Connected to the arm 12 are the conductors 18a and 18b, shown best in Fig. 6 of the drawings, which are electrically connected to the conductors 18, while the contacts 13b and 14b are connected to the conductors 20a, as shown

in Fig. 6 of the drawings, for completing the circuit through the battery 17 and the lamp 20, which is illuminated during centrifugal operation of the blimps 13 and 14, which pivot about their mounting pins 13a and 14a, respectively. It will be here noted that the illuminated blimp 13 is provided with openings 14d in the side wall thereof, and a ruby reflector 14e at the frontal end thereof, as shown in Figs. 2 and 6 of the drawings. It will be here noted that the electrical equipment in connection with the illuminated blimp 13 is identical to that as described in connection with the illuminated blimp 14.

The operation of my toy is substantially as follows: When it is desired to cause rotation of the blimp-supporting arm 12 about the axis of its shaft 12c, the winding handle 2 is pulled outwardly by its T-head 2a, causing the strap 4 to pass over the roller 3 and rotate the drum 5, causing extension of the spring 8 around the annular groove portion 5a of the drum. During rotation of the drum 5 in winding, the gears 6 and 7 are rotated, causing rotation of the shaft 9 and the pawl base 10, which actuates the pawl 11 in a rotary manner around the axis of the shaft 9, causing compression of the spring 11a each time the pawl 11 engages the blimp-supporting arm 12 at its end 11b. Thus, the pawl 11, during the winding operation of the drum 5, does not positively force the blimp-supporting arm 12. When the winding handle 2 is released, the spring 8 forces the gear 6 to rotate, causing increased speed of the gear 7 rotating the shaft 9, and the pawl 11 positively engages one side of the blimp-supporting arm 12 and is forced against its abutment 10b, on the pawl base 10, which causes positive forceful engagement of the pawl 11 on the arm 12, so that rotation of the illuminated blimps 13 and 14 about the axis of the shank 12c is accomplished. During rotation of the supporting arm 12 about the axis of the shank 12c centrifugal force affects the blimps 13 and 14, causing the same to pivot on the axes of the pins 13a and 14a, whereby outward movement thereof causes the contacts 13b and 14b to engage the contacts 15 and 16, respectively, on the ends of the arm 12, which completes the electric circuit to the lamps 20, as shown in Fig. 6 of the drawings, illuminating the interior of these blimps 13 and 14 automatically.

This lighting effect creates a very specific attraction to children at night, and is an automatic function of centrifugal force which takes place upon rotation of the blimp-supporting arm 12. It will be noted that the drum 5 may be continually wound by operating the winding handle 2, and that the pawl 11, in reverse to its driving directional movement, only resiliently engages the arm 12 and lightly passes thereunder, due to compression of the spring 11a. This permits the arm 12, together with the blimps 13 and 14, to rotate in uninterrupted movement, while the drum 5 is again wound, extending the spring 8, for further forceful rotational movement of the arm 12 and the illuminated blimps 13 and 14, as hereinbefore described.

Though I have shown and described a particular construction, combination and arrangement of parts and portions, I do not wish to be limited to this particular construction, combination and arrangement of parts and portions, but desire to include in the scope of my invention the construction, combination and arrangement substantially as set forth in the appended claims.

Having thus described my invention, what I claim as new and desire to secure by Letters Patent is:

1. In a toy of the class described, a blimp-supporting arm rotatable about its middle portion transversely of its axis, illuminated blimps suspended from said arm and pivoted thereto, switch means in connection with said illuminated blimps and said arm actuated with the pivotal movement of said blimps relative to said arm, a battery in each of said illuminated blimps, and a lamp electrically associated with said battery and said switch means, arranged to be illuminated when said blimps rotate about the axis of said arm, and are acted upon by centrifugal force, said arm having a centrally disposed shank, a bearing therefor, a resiliently mounted pawl engageable with said arm outwardly of its pivotal axis, gear means in connection with said pawl for rotating the same.

2. In a toy of the class described, a blimp-supporting arm rotatable about its middle portion transversely of its axis, illuminated blimps suspended from said arm and pivoted thereto, switch means in connection with said model blimps and said arm actuated with the pivotal movement of said blimps relative to said arm, a battery in each of said illuminated blimps and a lamp electrically associated with said battery and said switch means, arranged to be illuminated when said blimps rotate about the axis of said arm and are acted upon by centrifugal force, said arm having a centrally disposed shank, a bearing therefor, a resiliently mounted pawl engageable with said arm outwardly of its pivotal axis, gear means in connection with said pawl for rotating the same.

3. In a toy of the class described, a blimp-supporting arm rotatable about its middle portion transversely of its axis, illuminated blimps suspended from said arm and pivoted thereto, switch means in connection with said illuminated blimps and said arm actuated with the pivotal movement of said blimps relative to said arm, a battery in each of said illuminated blimps, and a lamp electrically associated with said battery and said switch means, arranged to be illuminated when said blimps rotate about the axis of said arm and are acted upon by centrifugal force, said arm having a centrally disposed shank, a bearing therefor, a resiliently mounted pawl engageable with said arm outwardly of its pivotal axis, gear means in connection with said pawl for rotating the same, a resilient motor in connection with said gear means.

4. In a toy of the class described, a blimp-supporting arm rotatable about its middle portion transversely of its axis, illuminated blimps suspended from said arm and pivoted thereto, switch means in connection with said illuminated blimps and said arm actuated with the pivotal movement of said blimps relative to said arm, a battery in each of said illuminated blimps, and a lamp electrically associated with said battery and said switch means, arranged to be illuminated when said blimps rotate about the axis of said arm and are acted upon by centrifugal force, said arm having a centrally disposed shank, a bearing therefor, a resiliently mounted pawl engageable with said arm outwardly of its pivotal axis, gear means in connection with said pawl for rotating the same, a resilient motor in connection with said gear means, said motor including a drum and a spring connected thereto, adapted to be wound therearound.

5. In a toy of the class described, a blimp-supporting arm rotatable about its middle portion transversely of its axis, illuminated blimps suspended from said arm and pivoted thereto, switch means in connection with said illuminated blimps and said arm actuated with the pivotal movement of said blimps relative to said arm, a battery in each of said illuminated blimps, and a lamp electrically associated with said battery and said switch means, arranged to be illuminated when said blimps rotate about the axis of said arm and are acted upon by centrifugal force, said arm having a centrally disposed shank, a bearing therefor, a resiliently mounted pawl engageable with said arm outwardly of its pivotal axis, gear means in connection with said pawl for rotating the same, a resilient motor in connection with said gear means.

connection with said gear means, said motor including a drum and a spring connected thereto, adapted to be wound therearound, a flexible belt wound around said drum, a roller over which said belt is extended, and a reciprocally mounted winding handle in connection with said belt for retracting the same and causing winding rotation of said drum and said spring therearound.
